Patented July 24, 1973

227,829

CHAIR WITH HEADREST OR SIMILAR ARTICLE

Odo Klose, Wuppertal-Elberfeld, Germany, assignor to
Giroflex-Entwicklungs-AG, Koblenz, Switzerland

Filed June 7, 1971, Ser. No. 150,889

Claims priority, application Switzerland Dec. 8, 1970

Term of patent 14 years

Int. Cl. D6—02

U.S. Cl. D6—31

FIG. 1 is a front view of my chair with headrest or similar article, incorporating my invention;

FIG. 2 is a side view thereof, the opposite side being identical to the side shown;

FIG. 3 is a rear view thereof; and

FIG. 4 is a perspective view thereof.

The bottom surface of my chair with headrest or similar article, not shown, is substantially flat.

I claim:

The ornamental design for a chair with headrest or similar article, as shown and described.
